CLAIM

We claim the ornamental design for a battery module, as shown and described.

DESCRIPTION

FIG. 1 is an isometric view of a first embodiment of a battery module.

FIG. 2 is a top plan view thereof;

FIG. 3 is a bottom plan view thereof;

FIG. 4 is a front side view thereof;

FIG. 5 is a right side view thereof;

FIG. 6 is a left side view thereof;

FIG. 7 is a rear side view thereof; and,

FIG. 8 is an isometric view of a second embodiment of a battery module.
